UNITED STATES PATENT OFFICE.

ALFRED ADAMS, OF BROOKLYN, NEW YORK.

INTERCHANGEABLE PARTITION-SECTION.

No. 856,198.

Specification of Letters Patent.

Patented June 11, 1907.

Application filed December 5, 1906. Serial No. 346,363.

To all whom it may concern:

Be it known that I, ALFRED ADAMS, a citizen of the United States, residing at 74 Henry street, Brooklyn, county of Kings, and State of New York, have invented certain new and useful Improvements in Interchangeable Partition-Sections, fully described and represented in the following specification and the accompanying drawings, forming a part 10 of the same.

The present invention relates to partitions for offices and similar apartments in which the partitions are commonly not extended to the ceiling, but in order to finish off their upper edge are provided with a sloping cornice. 15

The object of the invention is to construct such partitions and their cornices in sections, with complementary engaging devices upon their edges adapted to wholly conceal the 20 joints of the sections when erected in a partition.

The invention provides a new article of manufacture, as the partition sections with their cornices and means for closing the joints 25 can be manufactured of various widths and carried in stock, and may thus be fitted together and erected in an office or apartment without any carpenter work whatever upon the sections.

To sustain such a sectional partition in place, guide-strips are provided upon the floor and on the walls at the opposite ends of the partition, and means is provided upon the top of the cornice, where it will not be seen, for holding the top of the sections in alignment. The edges of the sections may 35 also, if desired, be furnished with latches to engage automatically when the sections are fitted together, and concealed means provided for disengaging the latch when required.

By this construction, the partition sections are not injured when erected and can therefore be taken down without injury when necessary, and used in another apartment. 45

The means for concealing the joints of the sections consists of pilaster projections formed to overlap one edge of each section and extended over the baseboard of the partition, with cornice blocks fitted upon the outside of the cornice and projected over the end of the same. The space between such projecting pilasters and cornice blocks forms a complementary engaging device, adapted to

fit the edge of any similar section. Angle- 55 sections and tee-sections may be used to unite the other sections at a corner or at a junction, provided such angle-sections are formed with the cornices and pilaster projections, and cornice blocks similar to those 60 upon the other sections.

The invention also includes a door-frame having a cornice like the other sections, and a door hinged therein, and one or both edges of the door-frame provided with the pilaster 65 projections and cornice blocks to engage interchangeably the other sections.

The floor and walls are furnished with a grooved plate or strip to engage the bottom edges of the sections including the door-frame; and to fill any given space, as twenty feet, with such a sectional partition and a doorway, a suitable door-frame is selected with a door hinged therein and the remainder 70 of the space filled with sections of suitable 75 width to fit between the doorway and the opposed walls.

The edges of the sections having no pilasters are adapted to fit into the grooved wall-strip, but to engage the edges having pilasters therewith, a piece of the same thickness as the partition, and one, two or more inches in width, is fitted to the groove between the pilasters and extended into the groove of the wall-strip, such piece serving to completely 85 fill the space not occupied by the partition sections. Such piece may be made of tapering or irregular width so as to compensate for any irregularities in the position of the walls. 90

Sections to form a corner or tee-joint may 90 be made of any desired angle and provided with a suitable portion of the cornice and with pilasters and cornice blocks upon one or both edges, and a very great advantage is obtained by making such corner sections in a 95 factory; as the baseboard, chair rails, and cornices upon a corner piece require to be made with a miter joint, which if made by hand and in the apartment where the partition is erected requires a great deal of time 100 and skilled labor; but if made in the factory such miter joints can all be made by machinery and the parts glued and secured together at very slight expense.

In office buildings, thousands of feet of 105 partition have been erected annually, which could not be taken down without more or less injury to the partition, and which could not be

employed in another space of greater or less width without very materially rebuilding, involving considerable expense; but by the present invention, the sections can be taken down without injury and can be erected again with very little loss of time in any place to which they are adapted, with other sections to fill any extra space, which sections can be readily supplied by the maker, who carries a stock of such partition sections on hand.

The invention will be understood by reference to the annexed drawing, in which

Figure 1 represents a partition composed of a door-frame and two other sections; Fig. 2 is a diagram showing in plan a door-frame and five other sections fitted between the walls, only the end sections being engaged with the wall-strips, and the remaining sections separated to show the interchangeable and complementary engaging devices in contiguity. Fig. 3 is an elevation of a section having the pilasters at one edge; Fig. 4 is an elevation of door-frame and door with pilasters at both edges, and the cornice blocks above the pilasters represented only by dotted lines. Fig. 5 is a vertical section at the middle of Fig. 4 with a floor and ceiling represented, as well as a floor-plate, wall-strip and upper section, engaged with the door section. Fig. 6 is a vertical section of the upper part of the door-frame, the section plane cutting through the pilasters and cornice blocks, and the view drawn upon a larger scale than Fig. 4; Fig. 7 is a perspective view of one of the cornice blocks; Fig. 8 shows the edges of two of the partition sections with a latch for locking the same, in section on line 8-8 in Fig. 9 at the edge of the latch. Fig. 9 is a plan of the same; Fig. 10 is a sectional plan showing the cornices of two of the sections (taken above the cornice) with the cornice blocks and dowels engaged. Fig. 11 is a perspective view of the floor-plate; Fig. 12 is a plan showing the application of corner and tee-sections; Fig. 13 is a plan of a corner section provided with pilasters; Fig. 14 is a plan of a corner section without pilasters; and Fig. 15 is a plan of a tee-section with pilasters.

Dotted lines, indicating the mitering of the cornice, are shown in Figs. 12 to 15.

A, B, designate two walls; A', B', wall-strips thereon between which partition sections C, D and E are shown fitted in Fig. 1; the section D consisting of the door and door-frame with pilasters *a* projected from opposite edges to form vertical grooves upon both sides of the frame, and the sections C and E having each one thin edge fitted to such grooves and the opposite edge provided with pilasters *a* adjacent to the wall-strips A' and B', filling pieces being fitted to the grooves in such pilasters and the adjacent wall-strips, the same as shown in Fig. 2.

A floor-plate C' is shown in Fig. 5 and Fig. 6, with groove *b* in the upper side to receive the lower edges of the partitions, such plate and the wall-strips serving amply to hold the partition in position, when the engaging devices are interlocked.

The stiles of the door-frame are connected at the bottom by a strip *b'* which forms a projection the whole width of the frame adapted to fill the groove *b* in the floor-plate C', thus holding the frame in line with the other sections of the partition, and making the floor-plate serve as a sill to the door which hangs above the same.

To secure the partitions more rigidly to one another and hold them more rigidly in place, one or more latches may be placed on one edge of each section between the pilasters, and a latch-guard provided upon the opposite edge of each section, adapted to interchangeably engage such latch or latches, as shown in Figs. 8 and 9.

The latch *c* is shown constructed with a shank *d* having a spring *e* thereunder which presses it normally downward, so that it automatically engages the guard *f* when the edge of one section is pressed toward another.

To facilitate the detachment of the latch when it is desired to take down the partition, a toe *d'* is projected from the shank in line with a push-pin *g* extended into the edge of one of the pilasters *a*, and pressure upon the pin *g* by a nail, lead pencil, or other means serves to lift the latch and permit the separation of the sections.

As the push-pin *g* is not upon the face of the pilaster, it is entirely invisible and furnishes a concealed means of detaching the latch when necessary. To conceal the joints between the cornices *h* upon the several sections, cornice blocks *i* are secured upon the cornice in line with the pilasters *a* and thus project over the ends of the cornice. Such cornice blocks are made internally of the same contour as the cornice itself and glued or otherwise secured thereon, and thus form a socket which closely fits the cornice upon an adjacent section and helps to greatly stiffen the joints of the sections.

Fig. 5 shows the appearance of the cornice intermediate to its ends, and Fig. 6 shows the end of one of the sections with the pilasters *a*, and cornice blocks *i* cross-hatched, clearly showing the space of the same size as the partition, between the pilasters and cornice blocks upon the opposite sides of the partition.

Where the cornice is formed, as shown in Figs. 4 and 5 with a thickened head *a'* independent of the molded projection, the pilaster is formed with a corresponding pilaster block *a''*, and the cornice blocks *i* being formed of the same cross-section or profile as

the cornice, the appearance of the partition is imitated in the pilaster projection at each joint.

The base-board *a* upon the corner section 5 is also shown with pilaster blocks *a'* overlapping the ends of the section in the same manner as the pilasters *a*, the pilaster blocks *a'* and the cornice blocks *i*; and the entire joint between the sections, from the top to the 10 bottom of the partition, is thus completely concealed, and concealed by such means that its presence is not even indicated, because pilasters are commonly used upon all partitions between the glass or wooden 15 panels to break up and ornament the surface. All these overlapping parts fit snugly upon the edges of the adjacent section and serve to support and stiffen the sections which are not engaged with the wall-strips.

20 To further stiffen the joint between the sections, dowel-pins *j* are, in Figs. 6 and 10, shown upon the head-piece of the partition at one end of the head, and corresponding holes *k* are shown in the opposite end of the 25 head, which fit the dowel-pins interchangeably upon any of the sections. Such pins are shown in Fig. 6 and in Fig. 10, where they are represented within the space bounded by the cornice blocks *i*, which protect 30 them from accidental injury when the separate sections are handled in transportation.

A further stiffening device is shown in 35 Figs. 6 and 10, where the head-piece of the partition is formed with a central groove *n* and a continuous bar *m* fitted in the same across the joints of the partitions, thus assisting to hold them in line, and such stiffening effect is produced whether the bar be secured in the groove *n*, or left loose to facilitate the taking down of the partition when- 40 ever required.

The majority of partitions are not ex- 45 tended to the ceiling, but where desired, the sectional partition is extended to the ceiling by placing upper sections *G* upon the top of the partition, guiding the same by a grooved plate *G'* attached to the top of the partition, and a grooved ceiling strip *H* attached to the ceiling. As the ceilings are not always ex- 50 actly parallel with the floor-line, the groove in the ceiling-strip may be made of one or more inches in depth, so as to clasp the upper edges of the sections *G*, whether the same extend to the full height or not. The 55 joints between the edges of the upper sections are shown in Fig. 1 covered by pilasters as with the main sections *C*, *D* and *E*.

A corner section adapted to fit interchangeably with the other sections is shown 60 in Fig. 13 formed with wings *I*, *I'*, at right angles to one another, with the cornice represented by dotted lines *h'*, the parts *a* designating the pilasters exposed upon the inner sides of the corner, the parts *a'* showing pi-

lasters upon the outer side of the corner, and 65 both pilasters projecting over the adjacent edges of the section, as in the door-frame *D*.

The baseboard *o* is shown upon the outer side of the corner with miter-joint *o'*, as is necessary upon a corner, and the cornice is 70 indicated by dotted lines *h'*, with the miter-joint of the same represented by dotted lines *h''*. Such section may be completely finished in the factory and adapted to fit any of the other sections interchangeably. The same 75 is true of the tee-section shown in Fig. 15, having a straight portion *J* forming two wings at its opposite ends provided respectively upon their inner and outer sides with pilasters *a*, *a'*, and a right angle wing *J'* having 80 pilasters *a''* at opposite sides, thus forming three grooved edges adapted to fit the plain edges of any of the other sections.

The corner section or tee-section may be built at other than a right angle and made 85 without pilasters, as shown in the section *K* in Fig. 14, having two wings set at an angle of 135 degrees to one another, to form an obtuse corner, as indicated in Fig. 12. In this figure, three partitions designated *L*, *M* 90 and *N* project out from a wall *P*, and a partition *Q* is connected with the partition *L* by a corner section with the partition *M* by a tee-section, and with the partition *N* by two of the angle sections *K*, between which a 95 door-frame *D* is shown fitted.

It is preferable in such partitions that the junction of the partition with a wall or with another partition should be ornamented with pilasters, and the sections *I* and *J* are thus 100 formed with the pilasters to furnish ornamental junctions of the partitions; and in Figs. 2 and 12 the junction of the partitions with the walls is also characterized by pilasters adjacent to the wall-strips *A'*. 105

Door-frames *D* are shown in the partitions *M* and *Q*, partition sections without pilasters being inserted between the door-frame in the partition *M* and the adjacent section, and also next to the door-frame in 110 the partition *Q*.

My claims to an interchangeable section provided with pilasters upon one edge are intended to cover a corner section, whether the pilaster projections be formed upon one 115 or more edges of the same.

To facilitate the insertion of the last section in a partition when erecting the same, the floor-plate, wall-strip, or pilaster upon one section may be detachable, as shown in the floor-plate in Fig. 11, where the wood at one side of the groove is represented secured by screws, and one of the outer pilasters *a'* in Fig. 15 is represented similarly secured. 120

Heretofore, it has been common where a 125 floor is uneven and varies in level, to cut the bottoms of partitions to fit the inequalities of the floor; but in my invention the floor-

plate C' is leveled first and the several sections set thereon. By thus furnishing a level base for the section, the cutting and disfiguring of the sections is avoided, and 5 they are enabled to make uniform joints upon their contiguous edges, and they can when their service in any location is ended, be readily detached from one another and set up in any other place for similar use.

10 Where the floor-plate is used upon an uneven floor, it is leveled by putting blocks under it at suitable intervals, and securing a molding upon the floor at the edges of the floor-plate to conceal the gap beneath the 15 plate.

By my construction, partitions having 20 cornices exactly like those now in use can be made in sections and erected in very little time and with very little noise, dirt, or interference with the tenants of an apartment, and can be taken down and removed with equal facility, as the only parts attached to the building are the strips upon the floor and walls.

25 Having thus set forth the nature of the invention what is claimed herein is:

1. As a new article of manufacture, interchangeable partition sections provided each with an attached section of cornice h and each 30 partition section having at one edge pilaster projections a to overlap the edge of an adjacent section, and the cornice provided with corresponding overlapping cornice blocks i having internal contour corresponding to 35 the profile of the cornice so as to snugly engage the same, the pilasters and cornice blocks i thus serving to wholly conceal the joint between the sections when erected.

2. As a new article of manufacture, interchangeable partition sections provided each 40 with an attached section of cornice h and each section having at one edge pilaster projections a to overlap the edge of an adjacent section and conceal the joint therewith, and 45 means projecting from the edge of the section between the pilaster projections for locking to the edge of the adjacent section.

3. As a new article of manufacture, interchangeable partition sections provided each 50 with an attached section of cornice h and each partition section having at one edge pilaster projections a to overlap the edge of an adjacent section and conceal the joint therewith, a latch projecting from the edge 55 of the section between the pilaster projections for engaging the edge of the adjacent section, and means concealed by the pilaster projection for disengaging such latch, to permit the separation of the sections when required.

4. As a new article of manufacture, interchangeable partition sections provided with a cornice, each section having one edge provided with pilaster projections to overlap the

edge of an adjacent section, and the cornice 65 provided at opposite ends respectively with dowels and with complementary dowel holes to engage the adjacent sections together.

5. In a partition unsupported at the top, the combination, with interchangeable partition sections, of the strip A' secured vertically upon the wall with groove to receive the edge of a section, and the sections provided each with an attached section of cornice h and formed upon one edge to fit the 70 groove in such wall-strip interchangeably, and upon the opposite edge with cornice blocks i, and with pilaster projections a forming a groove corresponding to that in the wall-strip, whereby the sections are 75 adapted interchangeably to engage one another or the groove in the wall-strip.

6. In a partition extending from floor to ceiling, the combination, with the floor-strip C' having groove b, of interchangeable 85 partition sections fitted each at the bottom to such groove and provided each with an attached section of cornice h and upon one edge with cornice blocks i and with pilaster projections a to engage the edges of opposed 90 sections, a grooved cap G' secured over the tops of all of the cornices, top sections G set in the said groove and provided each at one edge with overlapping pilaster projections to engage the adjacent top section, and the 95 ceiling-strip H having groove fitted to the upper edge of the top sections, with depth sufficient to compensate for variations in the height of the apartment and retain engagement with the sections G.

7. In a partition unsupported at the top, the combination, with interchangeable partition sections provided each upon one edge with pilaster projections forming a groove, and the opposite edges of the section adapted 100 to fit such grooves, of a floor-plate having a groove adapted to fit the bottoms of the sections, and a door-frame having door hung therein and provided with pilaster projections to engage the opposite edges of the 105 adjacent sections, and having at the bottom a tie-bar adapted to fill the groove of the floor-plate, whereby the floor-plate serves as 110 a door sill for the door.

8. In a partition unsupported at the top, 115 the combination, with interchangeable partition sections provided each with a section of cornice h and with pilaster projections a and cornice blocks i to engage the edge of an opposed section, and the tops of the cornices 120 having the coincident grooves n, of the strip m extended through such grooves, to hold the sections in line with one another.

9. In a partition, the combination, with interchangeable partition sections provided 125 each with a section of cornice h and with pilaster projections a and cornice blocks i to engage the edge of an opposed section, of a

corner section having wings projected at an angle to one another and provided with attached sections of cornice jointed at the same angle as the wings, and pilasters and cornice blocks projected from the edges of the wings to engage the edges of opposed sections.

5 In testimony whereof I have hereunto set

my hand in the presence of two subscribing witnesses.

ALFRED ADAMS.

Witnesses:
